CLAIM

We claim the ornamental design for a conveyor pulley including a wear indicator, as shown and described.

DESCRIPTION

FIG. 1 is a perspective view of a conveyor pulley including a wear indicator showing our new design;

FIG. 2 is a left side elevation view thereof;

FIG. 3 is an enlarged left side elevation view thereof; and, FIG. 4 is a top plan view thereof.

The dash broken lines shown in the figures are for the purpose of illustrating portions of the conveyor pulley including a wear indicator and form no part of the claimed design.
